UNITED STATES PATENT OFFICE.

FREDERICK LAMPLUGH, OF WILLESDEN JUNCTION, ENGLAND.

VALVE-GEAR FOR INTERNAL-COMBUSTION ENGINES.

1,081,051.

Specification of Letters Patent.

Patented Dec. 9, 1913.

Application filed December 27, 1911. Serial No. 628,055.

To all whom it may concern:

Be it known that I, FREDERICK LAMPLUGH, a subject of the King of Great Britain, residing at Willesden Junction, in the county of Middlesex, England, have invented new and useful Improvements in Valve-Gears for Internal-Combustion Engines, of which the following is a specification.

10 The object of the present invention is to construct improved mechanism for operating the sleeve valve of an internal combustion engine. According to the present invention I employ a compressed air chamber 15 and a pneumatic cylinder and in conjunction with such pneumatic means I may also employ a spring to move the valve in one direction. Thus should the pneumatic means or the spring fail the other will continue to operate. The valve is moved against the action of the air and spring by any usual mechanism such as a cam and lever.

The invention is illustrated in the accompanying drawings, in which:—

25 Figure 1 is a longitudinal section of a firing cylinder, crank shaft and means for operating the valve. Fig. 2 shows modified means for operating the valve rod.

The cylinder *a* is extended beyond the length required for the full stroke of the piston *b*, and in such extended space is fitted a split sleeve *c*, which has a sliding fit within the cylinder. The cylinder head or cover *a'* has a projection *a''* descending 35 therefrom, which fits the interior of the split sleeve valve *c*, and the center *a'''* of such head or cover *a'* is fitted with the firing plug.

40 The sleeve valve *c* covers the inlet port or ports *d* and a secondary or auxiliary exhaust port *e* closely adjoining, which latter, by means of the duct *e'* along the outside of the cylinder *a*, communicates with the primary exhaust port *e''*. The sleeve valve has an inlet port or ports *c''* which is or are brought, at the required time, into line with the inlet port or ports *d* in the cylinder *a*.

45 The opening of the primary exhaust port *e''*, by the piston overrunning it, will anticipate that of the secondary or auxiliary port *e*, the parts being so arranged that, until the cylinder *a* is relieved of pressure at the primary exhaust port *e''*, no movement is communicated to the sleeve valve *c*.

by its operating mechanism, this being done to prevent undue strain on the sleeve valve operating parts; which latter will then have no more work to do than to operate the sleeve valve *c*.

50 When the cylinder *a* is relieved of pressure by the opening of the primary exhaust port *e''*, the valve operating parts will cause the lower portion of the sleeve valve *c* to uncover the secondary or auxiliary exhaust port *e*; this allows, on the return or scavenging stroke of the piston *b*, for the residual gases to be driven out through the secondary or auxiliary exhaust port *e* and out through a duct *e'* leading to the primary exhaust port *e''*.

55 On a shaft *f* which receives motion from the crank shaft *g* by suitable gearing *h*, *h'*, *h''*, so proportioned as to give one revolution to the cam shaft *f* for two revolutions of the 75 crank shaft *g*, is fixed a cam *f'*, which acts upon a lever *f''* to give an upward motion to a rod *i*, which, at its upper end, is provided with a finger *i'* stepped into the split sleeve valve *c*. This finger *i'* may be formed 80 with a plurality of teeth fitting into recesses in the side of the sleeve valve *c*, as shown in Fig. 1. The cylinder is provided with a longitudinal opening *a'* in its side for the passage therethrough of the said finger *i'*, and each opening *a'* is covered and kept tight by the sleeve valve *c*.

85 The cam *f'* is so arranged that, until the cylinder *a* is relieved of pressure, no movement is given to the lever *f''* and finger *i'*.

90 The downward motion of the finger-carrying rod *i* is partly effected by a spring *i''* coiled around the same and bearing at one end against a fixed abutment *a''* and at the other end against a pin *i'''* fixed on the rod *i* 95 as shown in Fig. 1. The downward motion of the rod *i* and sleeve valve *c* is partly due to the suction of the piston *b* at the commencement of the induction stroke.

95 When the lowest part of the cam *f'* is in contact with the lever *f''*, the sleeve valve *c* will be in its lowest position, thereby bringing its inlet port or ports *c''* into line with the inlet port or ports *d* of the cylinder; then, on the outstroke, a charge will be 100 drawn in and the sleeve valve *c* lifted into its neutral position, covering both ports *d* and *e* as shown. In the cam's neutral or mid-position it will keep the sleeve valve *c* at rest during the compression and the 110

whole of the firing stroke, while pressure is exerted upon its interior surfaces.

The auxiliary exhaust *e* is opened by a raised portion of the cam *f'* operating at the end of the neutral period, consequently the cam is arranged to give a period of rest in its neutral position, a depression for the downward movement of the sleeve, and a positive movement above the neutral position for scavenging.

The spring *i*² may be omitted and the valve rod *i* may be kept in contact with the cam *f'* by pneumatic means, or the spring and pneumatic means may be employed conjointly.

The valve rod *i* has a lateral projection or pin *i*⁴ which enters a pneumatic cylinder *j* through a slot *j'* in the side thereof. Within the pneumatic cylinder *j* is a piston *k*, through which the pin *i*⁴ passes. The piston *k* is provided at its upper end with a pump leather *k'*. The cylinder *j* is connected with the compressed air or gas reservoir *l*, which is provided with any suitable form of inlet valve such as *l'* and a pressure gage *l*², the pressure of air or gas in the receiver *l* being obtained by any ordinary means. Above the pump leather *k'* is a certain amount of lubricating oil to keep the pump leather in good condition and tight.

In the modification shown in Fig. 2 the cylinders *j* are located above the valve rods *i* and in line therewith. Each cylinder *j* is fixed to or formed integral with the bushing *a*⁶ in which slides the upper end of the valve rod *i*. In this modification the piston *k* is provided with a short piston rod *k*², the end of which abuts against the top of the valve rod *i*. The compressed air or gas in the receiver *l* applies constant pressure on top of the piston *k* and keeps the valve rod *i* in contact with the lever *f*² and this latter in contact with the cam *f'*. When the valve rod *i* is lifted by the action of the cam *f'* and the piston *k* is forced upward in the cylinder *j* the air or gas is forced out of the cylinder *j* and compressed into the receiver *l*. *m* is a pipe for conveying lubricating oil to the bushings *a*⁶ to lubricate the valve rods *i*.

What I claim is:-

1. In means for operating the sleeve valve of an internal combustion engine, the combination of means for moving the sleeve valve in one direction, a closed compressed gas chamber having constant pressure therein, a cylinder connected to said chamber, a closed piston located in said cylinder and

means operated by the piston for moving the sleeve valve in the opposite direction. 60

2. In means for operating the sleeve valve of an internal combustion engine, the combination of means for moving the sleeve valve in one direction, and pneumatic means and a spring acting together for moving the sleeve in the opposite direction.

3. In means for operating the sleeve valve of an internal combustion motor, the combination of a finger stepped into the valve, a sliding rod carrying said finger, means for raising said rod, a chamber containing compressed gas, a cylinder connected to said chamber and a piston in said cylinder acting upon the sliding rod for lowering this latter, substantially as set forth. 75

4. In means for operating the sleeve valve of an internal combustion motor, the combination of a finger stepped into the valve, a sliding rod carrying said finger, means for raising the sliding rod, a chamber containing compressed gas, a cylinder connected to said chamber, a piston in said cylinder acting upon the sliding rod to lower the same and a spring surrounding the sliding rod which also assists to lower the sliding rod, substantially as set forth. 80

5. In means for operating the sleeve valve of an internal combustion motor, the combination of a finger stepped into the valve, a sliding rod carrying said finger, a lever for raising said rod, a cam for operating the lever, a chamber containing compressed gas, a cylinder connected to said chamber and a piston in said cylinder acting upon the sliding rod for keeping this latter in contact with the lever substantially as set forth. 90

6. In means for operating the sleeve valve of an internal combustion motor, the combination of a finger stepped into the valve, a sliding rod carrying said finger, a spring in compression around said sliding rod, a lever for raising said sliding rod, a cam for operating the lever, a chamber containing compressed gas, a cylinder connected to said chamber and a piston in said cylinder acting upon the sliding rod and acting in conjunction with the spring to keep the sliding rod in contact with the lever, substantially as set forth. 100

In witness whereof I have hereunto set my hand in presence of two witnesses.

FREDERICK LAMPLOUGH.
